(57) **CLAIM**

(**) Term: **14 Years**

We claim the ornamental design for a door for drum-type
washing machine, as shown and described.

(21) Appl. No.: **29/321,912**

DESCRIPTION

(22) Filed: **Jul. 25, 2008**

FIG. 1 is a front/right-side/top perspective view of a door for
drum-type washing machine showing our new design;

(51) **LOC (9) Cl.** **15-05**

FIG. 2 is a front-side elevational view thereof;

(52) **U.S. Cl.** **D32/25**

FIG. 3 is a rear-side elevational view thereof;

(58) **Field of Classification Search** D32/1,

FIG. 4 is a left-side elevational view thereof;

D32/5, 6, 8, 10, 25; 68/3 R, 12.01; 312/31;
34/523, 524

FIG. 5 is a right-side elevational view thereof;

See application file for complete search history.

FIG. 6 is a top-side elevational view thereof;

(56) **References Cited**

FIG. 7 is a bottom-side elevational view thereof; and,

U.S. PATENT DOCUMENTS

FIG. 8 is a front/right-side/top perspective view thereof show-

D518,250 S * 3/2006 Kirk et al. D32/6

D524,493 S * 7/2006 Choi et al. D32/6

D536,144 S * 1/2007 Seo et al. D32/6

D543,322 S * 5/2007 Usui et al. D32/6

ing that the same is attached to drum-type washing machine.

The broken lines of the present design in FIG. 8 are for
illustrative purpose only and no part of the claimed design.
